UNITED STATES PATENT OFFICE.

EDWARD P. KREEVOY, OF BOSTON, MASSACHUSETTS.

COUNTING MACHINE.

Application filed December 18, 1928. Serial No. 155,181.

This invention relates to a counting machine and has for its object to provide a device of simple and inexpensive construction and capable of being actuated manually, said device embodying therein means for resetting the indicating wheels to zero when necessary, and means for simultaneously locking the operating lever and resetting mechanism against accidental movement or 10 operation.

The invention consists in a counting machine as set forth in the following specification and particularly as pointed out in the claims thereof.

15 Referring to the drawings:

Figure 1 represents a front elevation of the counting mechanism, the casing being illustrated in section and the indicating wheels being broken away and partly illus-

20 trated in section.

Fig. 2 is a transverse section taken on the line 2—2 of Fig. 1, looking in the direction of the arrows on said line.

Fig. 3 is a transverse section taken on the 25 line 3—3 of Fig. 1, looking in the direction of the arrows on said line.

Fig. 4 is a detail plan view of a portion of the casing, illustrating the locking mechanism for the operating lever and resetting 30 mechanism.

Like numerals refer to like parts throughout the several views of the drawings.

In the drawings, 5 represents a casing constructed of any suitable material, and the 35 upper front corner of said casing is preferably curved at 6. A bracket 7 is mounted within the casing 5 and forms a support for shafts 8 and 9, said shafts being mounted in parallel relation in said bracket. Rigidly 40 fastened to the shaft 8 at one end thereof is a "units" indicating wheel 10 having numerals from 0 to 9 spaced at regular intervals around the periphery thereof. Also fast to the shaft 8, upon the opposite end thereof 45 from the indicating wheel 10, is a ratchet 12 preferably having nine teeth 13, all of the same size, and one tooth 14 which is cut deeper than the teeth 13, and the ratchet 12 is provided with a spring 15 which is 50 mounted in any suitable manner upon the bracket 7, and said spring is positioned in such relation to said ratchet as to permit rotation in one direction and to prevent its rotation in an opposite direction.

55 Rigidly fastened to one end of the shaft 9 is a "tens" indicating wheel 16, preferably

of a greater diameter than the diameter of the indicating wheel 10, and said indicating wheel 16 has a plurality of numerals from 0 to 25 spaced at regular intervals around 60 the periphery thereof, there being as many of said numerals as is permitted by the size of said wheel.

The indicating wheel 16 is positioned adjacent to and parallel with the indicating wheel 10, and said indicating wheels are so positioned within the casing that the peripheries thereof will pass close to the rear surface of the curved portion 6 of the casing 5, at which point the peripheries of said 70 indicating wheels will approximately align with each other.

Also rigidly fastened to the shaft 9, adjacent to the other end thereof from that upon which the indicating wheel 16 is located, are 75 ratchets 18 and 19 preferably of the same diameter and having the same number of teeth. The ratchet 19, however, is mounted upon the shaft 9 with its teeth positioned opposite to the teeth of the ratchet 18.

80 A spring 20 is provided for the ratchet 18, said spring being fastened in any suitable manner to the bracket 7 and positioned relatively to the ratchet 18 to permit the same to rotate in one direction and prevent its rotation in an opposite direction. The ratchet 18 is positioned in parallel relation with the ratchet 12 and said ratchets are also positioned so that at one point upon their peripheries one tooth of the ratchet 18 90 will align with a tooth of the ratchet 12. The ratchets 12 and 18 are actuated to rotate the indicating wheels 11 and 16 by an operating lever 21 which is pivotally mounted on the shaft 8, and said operating lever has 95 a handle portion 22 which projects outwardly from the casing 5 through a slot 23. provided in the top of said casing.

A spring 24 is provided for the purpose of normally holding the operating lever in 100 the position illustrated in Fig. 2 and for returning said operating lever to said position whenever said lever is moved forwardly.

105 A pawl 25 is pivotally attached at 26 to the operating lever 21, and a spring 27 is provided for said pawl, engaging the latter in a manner to hold the same in engagement with the teeth of the ratchet 12 and at intervals into engagement with the teeth of the ratchet 18. Each time that the operating lever 21 is moved forwardly the pawl 25 110 will engage a tooth of the ratchet 12, ro-

tating the latter a distance equal to the length on one of said teeth, and when the pawl engages the deep cut tooth 14 of said ratchet 12, the spring 27 will force said pawl downwardly in front of said tooth a sufficient amount to permit said pawl to engage one of the teeth of the ratchet 18, and the latter will rotate in unison with the ratchet 12 a distance equal to the length of one tooth.

Means are provided for the purpose of preventing accidental movement or operation of the operating lever 21 and the resetting ratchet 19, said means embodying therein a locking slide 28 slidably mounted in any suitable manner upon the undersurface of the top of the casing 5 and said slide is adapted to be moved into a notch 29 provided in the operating lever 21, at which time said lever is held in the position illustrated in Fig. 2.

A handle 30 is provided for the slide 28, said handle projecting through a slot 31 provided in the top of the casing 5. The opposite end portion of the slide 28 from that which interlocks with the operating lever 21 is formed into a pawl 32 which engages the teeth of the ratchet 19 and prevents the latter from being rotated in the same direction as the ratchet 12 whenever the operating lever is held against its operating movement.

A spring 33 is provided for the locking slide 28 and normally acts to hold said slide within the notch 29 of the operating lever as illustrated in Figs. 1 and 2. An operating knob 34 is rigidly fastened to an end of the shaft 9 that projects through the casing 5 and said operating knob is utilized whenever it is desired to reset the indicating wheels. An opening 35 is provided in the curved portion 6 of the casing 5 in front of the indicating wheels 10 and 16, and a transparent member 36 is provided at the rear of said opening, the numerals upon the indicating wheels 10 and 16 being visible through said opening and transparent member.

The general operation of the device hereinbefore specifically described is as follows:—Assuming that the indicating wheels 10 and 16 of the device are each set at 0, the locking slide 28 is moved out of engagement with the operating lever 21 by grasping the handle 30 of said locking slide and moving the latter from in front of the operating lever and out of engagement with the teeth of the ratchet 19. The operating lever is then rocked forwardly and the pawl 35 will successively engage the teeth 13 of the ratchet 12 rotating the latter one tooth with each operating movement of the lever and the numerals from 0 to 9 of the indicating wheel 10 will be exposed successively to view to the operator of the device through the opening 35 and transparent member 36.

When the pawl 25 finally engages the tooth 14 of the ratchet 12, said pawl will also engage one of the teeth of the ratchet 18, and as the 0 numeral of the indicating wheel 10 again comes into view the numeral 1 of the indicating wheel 16 will be brought into view and said numeral 1 will continue to remain in view until the ratchet 12 has been given another complete rotation, successively exposing the numerals 1 to 9 inclusive, when the pawl 25 will again engage the tooth 14 of the ratchet 12 and the ratchet 18 will again be rotated one tooth, again operating the indicating wheel 16 and exposing the numeral 2 to view. This operation may be repeated to the extent permitted by the indicating wheels which finally will again register 0.

If, however, prior to said indicating wheels registering 0, it is desired to reset the device, the operating knob 34 may be grasped and with the locking slide 28 out of engagement with both the lever 21 and the ratchet 19, the latter may be rotated by the knob 34 in the same direction as the ratchet 18 has formerly been rotated by the operating lever 21 and pawl 25 until the indicating wheel 16 registers 0. The indicating wheel 10 is returned to 0 by operating the lever 21.

In the accompanying drawing one form of my invention has been illustrated, but it is evident that many changes may be made in the construction of the device without departing from the spirit of the invention or the scope of the appended claims.

I claim:

1. A counting machine having, in combination, a casing provided with an opening therein, a plurality of shafts mounted in parallel relation in said casing, an indicating wheel of a different diameter upon each of said shafts, the peripheries of said indicating wheels aligned with each other at said opening, a ratchet for each of said indicating wheels, said ratchets being mounted adjacent to each other and in parallel relation upon each of said shafts, one of said ratchets having a tooth cut deeper than the other teeth thereon, an operating lever, and a pawl fast to said lever and adapted to rotate said indicating wheels, one of said ratchets being actuated by said pawl with each operating movement of said lever and both of said ratchets being actuated in unison when said pawl engages said deep cut tooth.

2. A counting machine having, in combination, a casing, a plurality of shafts mounted in parallel relation in said casing, an indicating wheel upon each of said shafts, side faces of said wheels being located adjacent to and parallel with each other, a ratchet for each of said indicating wheels, said ratchets being mounted adjacent to each other and in parallel relation upon each of said shafts, one of said ratchets having a tooth cut deeper than

the other teeth thereon, an operating lever, a pawl pivotally mounted upon said lever and adapted to engage both of said ratchets and thereby rotate said indicating wheels, one of 5 said ratchets being actuated by said pawl with each operating movement of said lever and both of said ratchets being actuated in unison when said pawl engages said deep cut tooth.

10 3. A counting machine having, in combination, a casing, a shaft rotatably mounted in said casing, an indicating wheel fast to said shaft, a ratchet also fast to said shaft and having a tooth cut deeper than the other 15 teeth thereon, another shaft rotatably mount-

ed in said casing and parallel to said first-named shaft, an indicating wheel and ratchet fast to said last-named shaft, an operating lever pivotally mounted upon said first-named shaft, a pawl pivotally mounted upon 20 said lever and adapted to rotate said indicating wheels, said first-named ratchet being actuated by said pawl with each operating movement of said lever, and both of said ratchets being actuated in unison by said 25 pawl when the latter engages said deep cut tooth.

In testimony whereof I have hereunto set my hand.

EDWARD P. KREEVOY.
